ELECTRONIC PULSE-POWER SUPPLY

Hampton J. Dailey, Bloomfield, and John J. Borzin, Newark, N. J., assignors to Westinghouse Electric Corporation, East Pittsburgh, Pa., a corporation of Pennsylvania

Application January 27, 1945, Serial No. 574,918

3 Claims. (Cl. 250—27)

1

In exhausting vacuum devices of the electrical art such as lamps and radio tubes, one of the main problems is the removal of gases in the various parts of the electrical device. The rate of gas evolution from such a device part is a function of the temperature of the part. The higher the temperature, the more rapid is the gas evolution. However, in attempting to out-gas an electrical vacuum device, it is found that there is a limit to the temperature at which the parts can be held steadily. This limit is usually due to the maximum average dissipation which can be handled safely without destroying the device being exhausted. Such temperature is usually around 1200° C. to 1500° C.

It has been found, however, that if the electrical vacuum device parts can be raised to a temperature far exceeding the maximum permissible steady temperature, but accomplished intermittently for relatively short intervals of time, that damage is avoided, whereas the rate of gas removal is increased several fold. Control of the length of pulse, interval between pulses, variation due to gas condition of the electrical evacuated device, and other considerations assume importance in the utilization of the intermittent application of heating current.

The invention accordingly has for its objects a realization of the aforementioned intermittent application of heating current with the controls indicated.

Other objects of the invention will appear to those skilled in the art to which the invention appertains, both by direct recitation thereof and by implication from the context as the description proceeds.

Referring to the accompanying drawing, Figures 1 and 2 thereof show two circuit arrangements embodying the present invention.

In said drawing, the electrical vacuum device, here shown as a radio tube, is designated by numeral 10 and is the device the gas removal from which is accomplished by the present invention. The apparatus constituting the physical embodiment of the invention provides output terminals X and Y to which appropriate connection may conveniently be made to the said electrical vacuum device. Input connection from a commercial line or other source of alternating current for supplying the heating current to output terminals X and Y, is designated as input terminals A and B. Full wave rectification of the current between input A, B and output X, Y, is provided, a bridge rectifier R being shown in Fig. 1, and a center tap rectifier R' being shown

2

in Fig. 2. In each instance a transformer T is provided, the secondary 11 of which is in series with the anode-cathode path through two triode electronic devices 12, forming part of and situated at the positive end of the rectifier. Flow of current through said anode-cathode path is under control of grids 13 of said triode electronic devices. Preferably said triode electronic devices are thyratrons, a characteristic of which is sharp cut-off by grid bias. Thus the duration of current flow from input A, B to output X, Y, and recurrence of the pulses are determined by the grid bias of the thyratrons, and the automatic control of that grid bias constitutes a feature of the present invention.

Describing in detail the preferred embodiment of the invention and showing of Fig. 1, it may be added that the main line rectifier R shown provides, in conjunction with the thyratrons 12, a pair of one-way electrical valves 14 of which crystals, copper oxide coated plates, and diode vacuum tubes are examples. The anodes 15 of these valves are connected, as by wire 16, and from that wire is a circuit wire 17 to output terminal Y. The cathodes 18 of said valves 14 are connected to the ends of the transformer secondary 11 and to the anodes of the thyratrons. The cathodes 19 of the thyratrons 12 are connected, as by wire 20, and leading therefrom is the other main circuit wire 21 to output terminal X.

The thyratron grids 13 are connected by a wire 22 in which two grid resistors 23 are interposed, each between a center tap 24 and one of said grids. From said center tap 24 a wire 25 makes connection with the anode 26 of another one-way valve 27 which for convenience will be referred to as the grid-control valve. A line 28 leads from the cathode 29 of said grid-control valve 27 to one end of the secondary of a timer-circuit transformer 30. The load on this timer-circuit transformer secondary is a condenser 31 connected at one side by wire 32 to the secondary at the end away from the grid control valve 27 and connected at its other side to the line from said valve to center tap 24, from which connection exists to the thyratron grids. As electron flow is always from minus to plus through the load, the combination of one-way grid control valve 27 and transformer 30, when voltage is applied to the transformer, will develop a negative charge on the side of the condenser connected with the thyratron grids, and values and characteristics of the thyratrons, valves, resistances, capacitance and current are computed and

selected so that the charge on condenser 31 will be adequate for making the thyratron grids negative to and beyond their cut-off value. Heating current to the tube or other electrical vacuum device 10 being out-gassed is thereby interrupted.

In the primary circuit of timer-circuit transformer 30 is a timer 33 of suitable construction, various makes being available on the market, and function of which is to repeatedly open and close the circuit in a constantly recurring cycle of current from the alternating current line feeding the primary of said transformer. When the timer 33 closes the circuit to the transformer, charge on the condenser takes place immediately, the thyratron grids are negatively biased and heating current to the electrical evacuated device is interrupted. When the timer breaks the supply circuit to the transformer 30, charge on condenser 31 dissipates through a resistance 34 in parallel with the condenser, thereby eliminating the negative bias on the thyratron grids and again permitting flow of heating current to the electrical evacuated device. It will now be clear that the construction provides for a flow of heating current when the timer circuit is open or non-conducting, and conversely, a stoppage of heating current when the timer circuit is closed or conducting.

It should be borne in mind that the limitation of permissible temperature for steady heating of the electrical device being out-gassed of 1200° C. to 1500° C. necessitates long periods of heating and evacuation. According to the present invention, short pulses of much higher temperature are applied to the said device, namely such temperatures as 2000° C. to 2200° C., with interposed off pulses of the heating current, and with the timer adjusted to apply the pulses at a rate at which the average dissipation of heat in the device being treated is within the capabilities of the device to accomplish without detriment. Satisfactory results have been attained in practice by utilizing a ratio of on to off periods of two to three. The timer is, however, adjustable and this ratio may be changed.

A feature of the invention furthermore contemplates inclusion of load-sensitive means for automatic protection against excessive heating current being applied while or when the device being treated is excessively gassy. Presence of excessive gas causes the device to draw more current, and this is taken advantage of as a control means for interrupting the said current. In the line 21 from the thyratron cathodes 19 to the output terminal X is provided a variable resistor 35, and between the resistor and said terminal X is connected a cathode 36 of an electronic control device 37 which is preferably a thyratron. The anode 38 of said electronic control device 37 connects to one end of the secondary of a transformer 39, the other end of said secondary being connected to the previously described secondary of the timer-circuit transformer and therefore connected to the dissipating resistance 34 and condenser 31. There is a similar resistance 40 to dissipating resistance 34 in series therewith and extending from wire 32 to the main line circuit wire 21 between rectifier T and the above mentioned variable resistor 35. The two said resistances are in series and constitute an electrical cross connection from wire 25 to main line circuit wire 21. In parallel to the resistances 34 and 40 across these same two wires 25 and 21 is a condenser 41. From the vicinity of connection of the main current wire 21 and 75

resistance 40 is a lead wire 42 to grid 43 of the electronic control device or thyratron 31, a source of potential, such as battery 44 being in series in said lead wire with the negative end toward the grid. This negative potential normally suffices to bias said grid 43 to cut-off so that no current flows in the cathode-anode circuit thereof. However, an excessive current to the electric device being degassed, due to excessive gas, for instance, and developing high voltage drop across variable resistor 35 then causes a positive or less negative bias on the grid 43 of the control device 37, which renders the cathode-anode circuit thereof conducting. This, in turn, through the combination of applied alternating current voltage from transformer 39 and control device 37 acting as a rectifier applies a negative charge on condenser 41 and negative bias to the grids 13 of thyratrons 12 of the main heating supply rectifier R to cut-off, and thus interrupts the heating supply current to output terminals X, Y. As soon as power is removed from the device being degassed, the voltage drop across variable resistor 35 disappears, control device 37 becomes non-conducting, condenser 41 discharges through resistors 34 and 40, and the negative bias is removed from the main rectifier thyratrons 12. Those thyratrons therefore become conductive and power is reapplied to the electrical evacuated device 10 on exhaust. As long as the excessively gassy condition of that device 10 prevails, the recurring on-off operation of control device 37 continues. But as soon as the excessively gassy condition clears up, the control device 37 is no longer rendered conductive and ceases to function actively to interrupt the heating current, and timer 33 acts to pulse the heating current. Condenser 41 across the grid-cathode circuit of the thyratrons of the main rectifier R will function to stabilize the operation of those thyratrons, and grid resistors 23 in series with the grids of those thyratrons will function to prevent the thyratrons from drawing excessive grid currents.

Referring now to the disclosure of Figure 2, main line rectifier R' is shown with its power transformer T having a center tap for one main line 17 to output terminal Y. Said rectifier R' also having two triode electronic devices 12 functioning as rectifier tubes and having grids 13 for control or cut-off purposes as above described. The cathodes 19 of these devices are joined by wire 20 from which leads a wire 21 to the other output terminal X. A biasing resistor 35a is included in connection 21. In shunt with the biasing resistor 35a is a line 47 in which is included a condenser 48, a one-way control valve 49 and one section 50 of a voltage divider resistance 51, which in its entirety connects across the main lines 17 and 21 between output terminals X and Y. The one-way control valve 49 may, as indicated for similarly illustrated devices 14 and 27 of the showing of Fig. 1, be any desired instrumentality such as a crystal, copper oxide coated plates or a diode electronic vacuum tube. It is arranged with its anode 52 connected to the condenser 48 and its cathode 53 to the voltage divider 51. Between said condenser 48 and said one-way control valve 49, a line 54 is connected which leads to the grids of rectifier triodes or thyratrons 12 of rectifier R'. This line 54 includes a variable resistor 55 beyond which is a cross connection 56 bridging condenser 48 back to shunt line 47 and including a second condenser 57 which consequently is in electrical

parallel to the first-mentioned condenser 48. At the opposite side of the second condenser 57 to variable resistor 55, and therefore having direct connection to the thyratron cathodes 19, is a resistance 58 beyond which is one branch 59 to a third condenser 60 and another branch 61 to a variable bias discharging resistor 62, the other sides of said third condenser 60 and bias discharging resistor 62 being connected by wire 63. This wire 63 also has a connection 64 back to shunt line 47, connecting therewith between one-way valve 49 and variable resistor 55. Said connection 64 includes therein another one-way valve 65 of suitable character and arranged with its cathode 66 toward the anode of the previously described one-way valve 49 and with its anode 67 toward the condenser-variable resistance connection 63. A bias discharging electronic device 68, which is preferably a thyratron having a cathode 69, anode 70 and grid 71, has its cathode connected to the line 54 to the grids of the power rectifier thyratrons through a biasing resistance 72 in that line, has its anode connected to line 61 at one end of bias discharging resistor 62 and has its grid connected to line 63 at the other end of said bias discharging resistor 62.

In operation, power rectifier R' applies full-wave rectified current to main lines 17 and 21, a portion thereof passing through the voltage divider resistance 51 including section 50 thereof. Due to shunt line 47, part of the current passes through that line and part through biasing resistor 35a. First condenser 48 is charged almost instantly through one-way valve 49 to the voltage developed across said resistor 35a minus the voltage drop in rectifier 49. The voltage across this first condenser 48 then starts charging the second condenser 57 through variable resistor 55. The voltage across the first condenser 48 also charges the third condenser 60 by way of connections 63, 64 and the second one-way valve 65. The polarity of the voltage on the side of the condensers having connection 54 to the power rectifier thyratron grids 13 is negative. When the potential across the second condenser 57 has risen to sufficiently high voltage, the negative charge biases the power rectifier thyratron grids beyond cut-off, and since the thyratrons then are non-conducting, the power supply is interrupted in main lines 17 and 21 to outputs Y and X respectively. As indicated, charge on the first condenser 48 exceeds that needed by the second condenser 57 for cut-off of the thyratrons before cut-off takes place, and after cut-off is effected, the excess charge continues to increase the charge on the second condenser 57. This action can give a time delay for the off period and is subject to increase or decrease by adjustment of variable resistor 55 between the two condensers. One-way valve 49 prevents first condenser 48 from discharging back through biasing resistor 35a.

During the charging period grid 71 of the biasing thyratron 68 is made negative so that thyratron is non-conductive, and the third condenser 60 may then be and is also charged through the second one-way valve 65 and connections 64 and 63 and through the first one-way valve 49 in series therewith. When the thyratrons 12 of the power rectifier are blocked by the negative bias applied to their grids 13, the third condenser begins discharging through variable bias discharging resistor 62, and when this voltage decreases sufficiently to render grid 71 of biasing thyratron 68 adequately more posi-

tive to bring it below cut-off, said thyratron 68 will fire or become conductive in its cathode-anode circuit and instantaneously removes the charge from the several condensers (condenser 57 in particular), and the bias from the grids 13 of the power rectifier thyratrons. Power may then again flow to the output X, Y and therefore to the electric evacuated device being outgassed applied thereto as in Fig. 1. This structure accordingly replaces use of a timer and its additional external circuit connection to the power source, and in addition to automatically pulsing the applied power, accomplishes timed cut-off and reapplication of the heating current. Adjustment of variable resistor 55 varies the time "on" of the heating current, whereas adjustment of variable bias discharging resistor 62, with thyratron 68, and like previously described variable resistance 35 and its thyratron 37, is a load-sensitive means and varies the time "off." Resistor 35a gives protection for excessively high current pulses through the device being outgassed, and voltage divider 51 protects against voltage increases across said device. Such voltage across the device on exhaust increases when said device "loses emission," especially when the voltage regulation of the system is poor.

We claim:

- 30 1. An electrical system comprising a rectifier having an input connection for alternating current to be rectified and having grid-controlled electronic devices for full-wave rectification of said alternating current and having output connections for the rectified current, means for pulsing the rectified current, said means automatically and repeatedly applying a negative bias to said grid controlled electronic devices thereby repeatedly interrupting and re-establishing current output therefrom in a pulsed cycle, and a load-sensitive means comprising mechanism rendered conductive in consequence of increase of current drawn by the load, said load-sensitive means being coupled with said electronic devices and connected supplementally to said pulsing means for also applying a negative bias to said grid-controlled electronic devices and thereby interrupting the pulsed output from the rectifier.
- 35 2. An electrical system comprising a rectifier having an input connection for alternating current to be rectified and having grid-controlled electronic devices for full-wave rectification of said alternating current and having output connections for the rectified current, means for pulsing the rectified current, said means automatically and repeatedly applying a negative bias to said grid controlled electronic devices thereby repeatedly interrupting and re-establishing current output therefrom in a pulsed cycle, and a load-sensitive means comprising a third electronic control device rendered increasingly conductive with increase in demand on the output and current drawn by the load, the said third electronic control device being coupled with the first-mentioned electronic devices and connected supplementally to said pulsing means for also applying a negative bias to said first-mentioned electronic devices and thereby interrupting the pulsed output from the rectifier.
- 40 3. An electrical system comprising a rectifier having an input connection for alternating current to be rectified and having grid-controlled electronic devices for full-wave rectification of said alternating current and having output connections for the rectified current, said means automatically and repeatedly applying a negative bias to said grid controlled electronic devices thereby repeatedly interrupting and re-establishing current output therefrom in a pulsed cycle, and a load-sensitive means comprising a third electronic control device rendered increasingly conductive with increase in demand on the output and current drawn by the load, the said third electronic control device being coupled with the first-mentioned electronic devices and connected supplementally to said pulsing means for also applying a negative bias to said first-mentioned electronic devices and thereby interrupting the pulsed output from the rectifier.
- 45 4. An electrical system comprising a rectifier having an input connection for alternating current to be rectified and having grid-controlled electronic devices for full-wave rectification of said alternating current and having output connections for the rectified current, said means automatically and repeatedly applying a negative bias to said grid controlled electronic devices thereby repeatedly interrupting and re-establishing current output therefrom in a pulsed cycle, and a load-sensitive means comprising a third electronic control device rendered increasingly conductive with increase in demand on the output and current drawn by the load, the said third electronic control device being coupled with the first-mentioned electronic devices and connected supplementally to said pulsing means for also applying a negative bias to said first-mentioned electronic devices and thereby interrupting the pulsed output from the rectifier.
- 50 5. An electrical system comprising a rectifier having an input connection for alternating current to be rectified and having grid-controlled electronic devices for full-wave rectification of said alternating current and having output connections for the rectified current, said means automatically and repeatedly applying a negative bias to said grid controlled electronic devices thereby repeatedly interrupting and re-establishing current output therefrom in a pulsed cycle, and a load-sensitive means comprising a third electronic control device rendered increasingly conductive with increase in demand on the output and current drawn by the load, the said third electronic control device being coupled with the first-mentioned electronic devices and connected supplementally to said pulsing means for also applying a negative bias to said first-mentioned electronic devices and thereby interrupting the pulsed output from the rectifier.
- 55 6. An electrical system comprising a rectifier having an input connection for alternating current to be rectified and having grid-controlled electronic devices for full-wave rectification of said alternating current and having output connections for the rectified current, said means automatically and repeatedly applying a negative bias to said grid controlled electronic devices thereby repeatedly interrupting and re-establishing current output therefrom in a pulsed cycle, and a load-sensitive means comprising a third electronic control device rendered increasingly conductive with increase in demand on the output and current drawn by the load, the said third electronic control device being coupled with the first-mentioned electronic devices and connected supplementally to said pulsing means for also applying a negative bias to said first-mentioned electronic devices and thereby interrupting the pulsed output from the rectifier.
- 60 7. An electrical system comprising a rectifier having an input connection for alternating current to be rectified and having grid-controlled electronic devices for full-wave rectification of said alternating current and having output connections for the rectified current, said means automatically and repeatedly applying a negative bias to said grid controlled electronic devices thereby repeatedly interrupting and re-establishing current output therefrom in a pulsed cycle, and a load-sensitive means comprising a third electronic control device rendered increasingly conductive with increase in demand on the output and current drawn by the load, the said third electronic control device being coupled with the first-mentioned electronic devices and connected supplementally to said pulsing means for also applying a negative bias to said first-mentioned electronic devices and thereby interrupting the pulsed output from the rectifier.
- 65 8. An electrical system comprising a rectifier having an input connection for alternating current to be rectified and having grid-controlled electronic devices for full-wave rectification of said alternating current and having output connections for the rectified current, said means automatically and repeatedly applying a negative bias to said grid controlled electronic devices thereby repeatedly interrupting and re-establishing current output therefrom in a pulsed cycle, and a load-sensitive means comprising a third electronic control device rendered increasingly conductive with increase in demand on the output and current drawn by the load, the said third electronic control device being coupled with the first-mentioned electronic devices and connected supplementally to said pulsing means for also applying a negative bias to said first-mentioned electronic devices and thereby interrupting the pulsed output from the rectifier.
- 70 9. An electrical system comprising a rectifier having an input connection for alternating current to be rectified and having grid-controlled electronic devices for full-wave rectification of said alternating current and having output connections for the rectified current, said means automatically and repeatedly applying a negative bias to said grid controlled electronic devices thereby repeatedly interrupting and re-establishing current output therefrom in a pulsed cycle, and a load-sensitive means comprising a third electronic control device rendered increasingly conductive with increase in demand on the output and current drawn by the load, the said third electronic control device being coupled with the first-mentioned electronic devices and connected supplementally to said pulsing means for also applying a negative bias to said first-mentioned electronic devices and thereby interrupting the pulsed output from the rectifier.
- 75 10. An electrical system comprising a rectifier having an input connection for alternating current to be rectified and having grid-controlled electronic devices for full-wave rectification of said alternating current and having output connections for the rectified current, said means automatically and repeatedly applying a negative bias to said grid controlled electronic devices thereby repeatedly interrupting and re-establishing current output therefrom in a pulsed cycle, and a load-sensitive means comprising a third electronic control device rendered increasingly conductive with increase in demand on the output and current drawn by the load, the said third electronic control device being coupled with the first-mentioned electronic devices and connected supplementally to said pulsing means for also applying a negative bias to said first-mentioned electronic devices and thereby interrupting the pulsed output from the rectifier.

nections for the rectified current, means for pulsing the rectified current, said means automatically and repeatedly applying a negative bias to said grid controlled electronic devices thereby repeatedly interrupting and re-establishing current output therefrom in a pulsed cycle, and a load-sensieive means comprising a third electronic control device having a grid rendered less negative by increased voltage drop caused by increase in demand on the output and current drawn by the load, the said third electronic control device being coupled with the first-mentioned electronic devices and connected supple- 15 mentally to said pulsing means for also applying a negative bias to said first-mentioned electronic devices and thereby interrupting the pulsed output from the rectifier.
